(57) **CLAIM**

The ornamental design for a rustic torched wood wall-mounted shelf, as shown and described.

DESCRIPTION

This patent contains at least one drawing/photograph executed in color. Copies of this patent with colored drawing(s)/photograph(s) will be provided by the Office upon request and payment of the necessary fee.

FIG. 1 is a front, top perspective view of a rustic torched wood wall-mounted shelf, showing my new design.

FIG. 2 is a front elevational view of the invention.

FIG. 3 is a rear elevational view of the invention.

FIG. 4 is a top plan view of the invention.

FIG. 5 is a bottom plan view of the invention.

FIG. 6 is a right side elevational view of the invention; and, FIG. 7 is a left elevational view of the invention.
